UNITED STATES PATENT OFFICE.

CLARENCE WINFRED SPICER, OF ITHACA, NEW YORK.

LIQUID-FUEL BURNER.

SPECIFICATION forming part of Letters Patent No. 728,140, dated May 12, 1903.

Application filed July 22, 1902. Serial No. 116,501. (No model.)

To all whom it may concern:

Be it known that I, CLARENCE WINFRED SPICER, a citizen of the United States, residing at Ithaca, in the county of Tompkins and State of New York, have invented certain new and useful Improvements in Liquid-Fuel Burners; and I do hereby declare the following to be a full, clear, and exact description of the invention, such as will enable others skilled in the art to which it appertains to make and use the same.

My invention relates to improvements in liquid-fuel burners or furnaces; and it consists in the novel means of introducing the liquid fuel and vaporizing the same and in the novel structure of the burner.

The burner herein described is particularly intended to use petroleum-oils, either crude or refined, in the form of what is known in the market as "kerosene," and similar oils which are too heavy for use in the burners of most steam-carriages of the present day.

My burner or furnace is adapted for use in connection with steam-boilers and for other uses to which burners employing liquid or gaseous fuel are applicable.

The objects of my invention are to employ heavier petroleum-oils than may be employed with satisfactory results in most liquid-fuel burners now in use and avoid the use of a generator directly heated by the flame of the burner for heating the oil prior to its passage into the burner proper, to avoid fouling of the burner, the deposition of soot, and a smoky flame, to avoid the use of a torch for starting the burner and to make the burner substantially self-starting, and generally to improve the structure of the burner and make the same as simple, compact, efficient, durable, and easy of management as possible.

I will now proceed to describe my invention with reference to the accompanying drawings, in which burners embodying my invention are illustrated, and will then point out the novel features in claims.

In the said drawings, Figure 1 shows a central vertical section of my burner applied to a steam-boiler. Fig. 2 is a top view of the two. Fig. 3 is a central longitudinal section of one of the atomizers. Fig. 4 is a view similar to Fig. 1, showing another form of my burner in which a mixing-chamber is pro-

vided with the usual air-flues. Fig. 5 is a top view of this second form of burner.

According to my invention the liquid fuel is not simply sprayed into a mixing-chamber, as is the case in one type of liquid-fuel burner commonly in use, nor is it heated by passing it through a generator exposed to the direct action of the flame before it has passed into the mixing-chamber, as in another type of burner commonly in use. The first of these methods is not applicable in the burning of the heavier petroleum-oils, such as kerosene or crude petroleum, since a considerable proportion of the constituents of such oils cannot be vaporized successfully in a burner under such conditions. The use of a generator is to be avoided, if possible, since the oil in passing through such generator is apt to be overheated, with the result that it suffers decomposition. Commercial kerosene-oil consists of a number of hydrocarbon oils of different specific gravities, the heavier oils being in solution in the lighter oils, and the same is true to a much greater extent of crude petroleum. Now if either of these oils be overheated while in a liquid state the lighter constituents are evaporated, and as a necessary result the heavier constituents are deposited. This is what is apt to occur if kerosene or crude petroleum be used in burners having generators such as above mentioned.

According to my invention the oil to be burned is atomized by means of a jet of some gas, preferably superheated steam or highly-heated air, the atomized vapor thus produced being passed into a mixing-chamber, which preferably is also heated to a temperature considerably above that of the atmosphere. In this chamber the atomized vapor of oil is mixed with air and then passing through suitable small orifices encounters the flame and is burned. The result of this manner of treating the oil is that it is gradually heated, first by the gas used to atomize it and thereafter by the heat of the mixing-chamber, yet because this second heating of the oil is conducted with the latter in an atomized condition no portion of the oil is overheated, and so no tendency to decomposition of the oil, or "cracking," as it is termed, results.

I am aware that it is old to spray petroleum-oils into the fire-boxes of locomotives and

similar boilers by means of air or steam under pressure. In such cases, however, combustion begins at or near the spraying-nozzle or atomizer, and the combustion is attended by a loud roaring noise, which in many cases is exceedingly objectionable. The burner herein described differs from this class of spraying or atomizing burners in that a mixing-chamber is interposed between the atomizer and the flame, with the result that air is thoroughly mixed with the atomized vapor before combustion, and the vapor issues from the burner-orifices at a relatively low rate of speed, and therefore the roaring noise above mentioned is avoided, and at the same time it is possible to obtain from the same burner a blue or smokeless flame through a wide range of rate of combustion of the fuel.

Referring now to the accompanying drawings and at first to Figs. 1 to 3 thereof, the said drawings show the lower portion of a boiler 1, having a combustion-chamber 2, beneath which is a mixing-chamber 3, separated from the combustion-chamber 2 by a foraminous plate or screen 4. Some distance above this plate 4 are superheating-coils 5, and between them and said plate are baffle-plates or deflectors 6. At one side are orifices 7 and 8 for the introduction of air and fuel, orifice 7 being above the foraminous plate 4 and orifice 8 below the same. Opposite these orifices are atomizers 9 and 10, both connected to a fuel-supply pipe 11 and to a pipe 12, leading from the heat-coils 5. Another pipe 13 may supply steam or air under pressure to these coils.

The atomizers 9 and 10 are of the well-known construction shown in detail in Fig. 3. Any suitable atomizing device capable of atomizing oils such as mentioned by the use of air, steam, or othersuitable gas under pressure may be used. The atomizer 9 is arranged to project a jet of atomized-oil vapor toward the first baffle-plate 6.

In starting my burner into operation if steam under pressure is not available compressed air may be used. To this end pipe 13 may be connected to any suitable source of supply of air under pressure, or if no such source be convenient and if the pipe 13 be connected to the boiler 1, as will ordinarily be the case, air may be pumped into this boiler until a gage-pressure of fifteen or twenty pounds exists, after which the valves leading to the atomizer 9 may be opened and the jet of atomized-oil vapor issuing from the atomizer ignited. The flame thus produced impinges against the first baffle-plate 6 and being deflected thereby impinges against the second baffle-plates, and so on, and passes upward, heating the coils 5 and the water in the boiler and starting the generation of steam. A considerable proportion of the heat thus produced in the combustion-chamber is deflected downward by the baffle-plates, so as to heat the walls of the mixing-chamber 3 and the air therein. After a short time and when

these parts have been sufficiently heated the valves leading to atomizer 10 may be opened. The atomized-oil vapor issuing therefrom carries with it into the mixing-chamber a large proportion of air and becomes mixed therewith. The highly-heated steam or air which atomizes this oil in the atomizer 10 serves to heat the same to a considerable extent, and this heating is continued in the mixing-chamber through the heat radiated from the wall thereof, so that the mixture of oil vapor and air issuing from the fine perforations in the burner-plate 4 is at a temperature to permit smokeless combustion of the oil vapor in the combustion-chamber 2 with a blue or colorless flame. In thus starting the burner the air-pressure used should be maintained at a minimum of from twelve to fifteen pounds gage-pressure until the generation of steam renders the further supply of air unnecessary. After the atomizer 10 is in full operation atomizer 9 may be shut off, or a slow action of this atomizer may be permitted and the flame therefrom used as a pilot-flame.

Atomizer 9 is so located and is preferably of such size that it may serve not only for heating the mixing-chamber, but for raising steam, and may be used in place of atomizer 10 and the mixing-chamber in case either of these parts should be disabled. In using the atomizer 9 in starting up only a portion of the heat generated by it is absorbed in heating the mixing-chamber. The remainder is utilized to heat the boiler and its contents, thus making it possible to raise steam very rapidly.

The mixing-chamber, it will be noted, is a single unitary chamber, without small branches and without sharp turns, around which the vapor must pass on its way to the perforations in the burner-plate 4, and therefore the oil particles will not be separated from the current of air or air and steam carrying them by inertia action.

It is not necessary to supply the oil to the atomizers under pressure, since the atomizers are capable of acting like injectors to lift the oil to them.

The mixing-chamber of the burner shown in Figs. 1 and 2 differs from the corresponding chambers of similar burners now in use in that all the air required for the consumption of the oil is taken in through the opening 8, the burner being without the usual air flues or thimbles by which air is carried into the combustion-chamber without passing through the mixing-chamber. As a result the air to supply the burner may be drawn from any convenient point, even from a point distant from the burner, by connecting a suitable air-pipe to the opening 8, and air may even be supplied to the burner under pressure. The top plate 4 of the burner may be a metal plate provided with narrow cuts or slots, as shown, (the width of these slots being necessarily exaggerated in the drawings,) or the said top plate may contain minute per-

forations formed by punching or drilling or similar action, or, again, the top plate may be a simple netting of wire-gauze. In any case the openings should preferably be so small that the flame will not pass backward through them, though of course if the air and oil-vapor be supplied to the burner at a rate such that the gas issues through the orifices of the plate 4 at a speed greater than the speed of propagation of flame backward through such a gas the size of the openings in plate 4 is less important. A burner thus constructed has nothing in its interior to impede unduly the flow of the combustible vapor to its burner-orifices; but instead of using a mixing-chamber such as shown in Fig. 1 I may use a mixing-chamber of the ordinary type. This is shown in Fig. 4, in which the mixing-chamber 14 is provided with the ordinary flues or thimbles 15, through which air is admitted to the interior of the combustion-chamber without passing through the mixing-chamber. The operation of this burner is the same as that above described. Likewise the mixing-chamber of the burner shown in Figs. 1 and 2 may be used in burning gasolene and similar light oils without using atomizers, the oil being sprayed into said chamber in the ordinary manner.

30 It is obvious that my invention is susceptible to many variations and modifications, and I do not limit myself to the particular details of construction herein illustrated and described.

35 What I claim is—

1. A burner of the class described, adapted for use in connection with steam-generators, comprising a mixing-chamber, a flame-chamber, an atomizer arranged to project an atomized vapor of oil into the mixing-chamber, an atomizing-burner for heating the mixing-chamber, arranged to project atomized vapor of oil into said flame-chamber at a point which is intermediate the mixing-chamber and steam-generator when the burner is connected to said generator, and connections for supplying oil and fluid under pressure to atomize the oil.

2. A burner of the class described, adapted for use in connection with steam-generators, comprising a mixing-chamber, a flame-chamber, an atomizer arranged to project an atom-

ized vapor of oil into the mixing-chamber, an atomizing-burner for heating the mixing-chamber, arranged to project atomized vapor of oil into said flame-chamber at a point which is intermediate the mixing-chamber and steam-generator when the burner is connected to said generator, means for supplying oil, and means for supplying fluid under pressure to atomize the oil, comprising a superheater.

3. A burner of the class described, adapted for use in connection with steam-generators, comprising a mixing-chamber, a flame-chamber, an atomizer arranged to project an atomized vapor of oil into the mixing-chamber, an atomizing-burner for heating the mixing-chamber, arranged to project atomized vapor of oil into the flame-chamber at a point which is intermediate the mixing-chamber and steam-generator when the burner is connected to said generator, and a baffle in the path of the jet from said atomizing-burner.

4. The combination with a steam-generator, of a burner comprising a mixing-chamber, a flame-chamber intermediate the mixing-chamber and the generator, an atomizer arranged to project an atomized vapor of oil into the mixing-chamber, a burner for heating the mixing-chamber, arranged to project flame into said flame-chamber at a point intermediate the mixing-chamber and generator, and connections for supplying oil and fluid under pressure to the atomizer.

5. The combination, with a steam-generator, of a burner comprising a hollow disk-like mixing-chamber having in one of its substantially flat sides a plurality of orifices for the escape of combustible vapor, an atomizer arranged to project an atomized vapor of oil into the mixing-chamber, a flame-chamber intermediate the mixing-chamber and generator, a burner for heating the mixing-chamber, arranged to project flame into said flame-chamber at a point intermediate the mixing-chamber and generator, and connections for supplying oil and superheated steam under pressure to the burner.

In testimony whereof I affix my signature in the presence of two witnesses.

CLARENCE WINFRED SPICER.
